GOLF CLUB

William Hutchison, Evanston, Ill., assignor of one-fifth to Alexander Cunningham, one-fifth to John F. Hutchison, and one-fifth to Carleton Blunt, all of Evanston, Ill.

Application January 28, 1931, Serial No. 511,734

8 Claims. (Cl. 273—80)

The present invention relates to a golf club, and more in particular to a novel shaft, and means for attaching said shaft to the club head.

Among the objects of the present invention is to provide a novel shaft construction for a golf club, the shaft being substantially triangular, provided with a cutting edge or leading apex, and a trailing plane surface at the rear thereof. In prior constructions of golf clubs, and particularly where metal shafts are employed, the average golfer has considerable difficulty in controlling his stroke, caused primarily by the fact that the club head is raised or taken back too rapidly on the upstroke. This too rapid backswing causes the golfer to shift or change his stance, raise his head, take his eye off the ball or lose control of the club, with the result that he hooks, slices or dubs his shot, or otherwise fails to properly execute the stroke. It further prevents the average golfer from securing the proper rhythm in his swing, which necessarily means his shots are poorly executed, his total score mounts or remains relatively high, and he frequently quits the game in disgust.

By means of the present construction of shaft, more wind resisting surface area is exposed on the upstroke or back swing, the air resistance on the rear surface of the shaft preventing, or tending to prevent a too rapid back swing.

A further object of the invention is the provision of a shaft having a flat, or substantially flat rear surface extending for substantially the full length of the shaft, said flat or plane surface providing means for increasing the air resistance against the rear surface of the shaft on the upstroke or back swing.

A still further object is to provide a shaft having a plane or flat rear surface, and the front thereof tapered or stream-lined in order to decrease or minimize the air resistance on the down-stroke.

Another object of the invention is the provision of a flat or plane rear surface on the shaft, disposed parallel to, or in parallel relation with the face or striking surface of the club head, thus providing means for properly aligning the club head with the ball. This feature is of great importance to the average golfer, as by properly aligning the rear flat face, or the edges of the rear face, or the shaft; i. e. positioning this rear face perpendicular to the hole or intended flight of the ball, it is possible to secure greater accuracy to the drive. Although the drawing discloses the novel shaft as attached to a driver or wood club, it is to be understood that the same is

equally adapted to iron club heads, the only distinction being that in iron clubs, the flat or substantially flat face of the shaft is positioned parallel to the lower edge of the iron club head, and not parallel to the face thereof.

A further object of the invention is the provision of a club head provided with an opening of the same configuration as the shaft of the club and adapted to receive the end thereof. The opening and shaft being substantially triangular in shape, such shaft and opening provides an efficient interlocking means to prevent twisting of the shaft in the club head. Another object is to provide a metal shaft substantially triangular in shape whereby to provide a more efficient construction.

Another object is the provision of the shank or hose of an iron club with an opening of a configuration to receive a shaft of substantially triangular shape, the outer contour of the shank or hose being also substantially triangular in shape, such shank or hose providing aligning means for the club head.

A still further object of the invention is to provide a shaft which is substantially triangular in shape, certain or all of the sides thereof being slightly dished or concaved.

Further objects are to provide a construction of maximum simplicity, efficiency, economy and ease of assembly, and alignment, and such further objects, advantages and capabilities as will later more fully appear, and are inherently possessed thereby.

The invention further resides in the combination, construction and arrangement of parts illustrated in the accompanying drawing, and while there is shown therein a preferred embodiment, it is to be understood that the same is susceptible of modification and change, and comprehends other details, arrangements of parts, features and constructions, without departing from the spirit of the invention.

Referring to the drawing:

Fig. 1 is a view in side elevation of one form of the invention.

Fig. 2 is a view similar to Fig. 1 but disclosing an alternate construction.

Fig. 3 is a view similar to Figs. 1 and 2, but disclosing a further alternate construction.

Fig. 4 is a fragmentary view in side elevation of the handle and shaft construction.

Fig. 5 is a fragmentary view in vertical cross section through the club head and disclosing the interconnection between the shaft and club head.

Fig. 6 is a fragmentary cross sectional view

taken in a plane represented by the line 6—6 of Fig. 1.

Figs. 7 and 8 are cross sectional views taken in planes represented by the lines 7—7 and 8—8, respectively, of Fig. 1.

Figs. 9 and 10 are cross sectional views taken in planes represented by the lines 9—9 and 10—10, respectively, of Fig. 2.

Figs. 11 and 12 are cross sectional views taken in planes represented by the lines 11—11 and 12—12, respectively, of Fig. 3.

Fig. 13 is a fragmentary cross sectional view taken through the shaft and shank or hose of an iron club, disclosing another embodiment of the invention.

Referring more particularly to the disclosure in the drawing, and more especially to the embodiment selected to illustrate the invention in Fig. 1, the construction comprises a golf club 20 provided with a handle 1, shaft 2, and club head 3. As disclosed, the handle and shaft are made integral, although the same may be made separate and connected or combined in any suitable manner.

The shaft 2, disclosed more particularly in Figs. 7 and 8 comprises a structure of triangular shape having a leading or front edge 4 and side surfaces 5 and 6, along with a trailing or rear surface 7. The trailing plane surface 7 at the rear of the shaft provides more air resisting surface area on the upstroke or back swing of the shaft, than is possible with the usual curved surfaces of the cylindrical or elliptical shaft now in use. The rear side of trailing surface 7 prevents, or tends to prevent a too rapid back swing, thus eliminating to a marked degree, the difficulties of the average golfer in controlling his stroke, caused primarily by the club head being raised too rapidly on the up-stroke.

The apex or leading edge 4 and the sides 5 and 6 provide a tapered or stream lined structure which decreases the air resistance on the down-stroke of the club head and shaft. The configuration and arrangement of the shaft relative to the shape of the club head also tends to lessen the possibilities of the club head twisting in the hands for the reason that after the golfer becomes accustomed to the use of this form of shaft, he will be readily apprised of the shifting or twisting of the shaft and club head by reason of the difference in air resistance encountered. When the club is swung properly the flat surface on the rear portion of the shaft will resist the air on the upswing and when improperly used a rear edge of the shaft will cut the air on the upstroke permitting too fast a back swing. The same would be true as to the down stroke in that when properly held the apex or cutting edge would pass through the air with the minimum of resistance and when improperly held a flat surface would offer considerably more air resistance. Thus there would be a difference in the "feel" of the club.

In Figs. 2, 9 and 10, there is disclosed an alternate or modified form of shaft 8 in which the apex 9 is formed by the merging of the concaved sides 10 and 11. This structure provides a further stream lining of the golf shaft. In Figs. 3, 11 and 12, there is disclosed a further alternate or modified construction in which the trailing surface 12, as well as the sides 10 and 11 are concaved.

In order to provide an efficient interlocking means between the end of the shaft and the club head, the club head 3 is provided with an

opening 14 of a configuration adapted to receive the ends of the shafts 2, 8 and 13. When the ends of the shafts are in the position shown in Fig. 5, there is no possibility of the shaft turning in the club head, and thus an efficient interconnecting means is provided. Any suitable means such as a pin (not shown), glue, or the like, may be provided for retaining the shaft and preventing the same from being withdrawn from the club head. Although Fig. 6 merely discloses a shaft of the form disclosed in Figs. 1, 7 and 8, inserted in a club head, it is to be understood that the club head may be provided with openings of a configuration to conformably receive the ends of the shafts 8 and 13, as disclosed in Figs. 2 and 3.

The present construction of shafts provides an efficient aligning means for properly aligning the club head with the ball. Regardless whether the club head is constructed of wood or metal, or of any of the various forms used in playing the game of golf, the rear surface 7 of the form of shafts disclosed in Figs. 1 and 2, is disposed parallel to the lower edge of the face of the club head, so that when the golfer aligns the face 1, 25 or more particularly the edges of the face 1, he can feel assured that his club head is properly aligned with the ball; i. e. the face 1 or edges thereof, and the face 15 of the club head, is disposed perpendicular to the intended line of flight of the ball. Although the face 12 of the shaft 13 disclosed in Fig. 3 of the drawing is concaved, nevertheless, the same aligning feature is present in this construction.

In Fig. 13 is disclosed an embodiment in which 35 an iron club 16 is provided with a hose or shank 17 provided with an opening adapted to receive an end of a substantially triangular shaped shaft 2, the outer contour of the hose or shank 17 being of the same or substantially the same configuration as the shaft; i. e. provided with a leading edge facing the intended line of flight of the ball to decrease air resistance on the down stroke, and a trailing surface perpendicular to the intended line of flight, and providing increased wind resistance on the upstroke, said trailing surface and leading edge providing additional aligning means when used with the present construction of shaft, or the primary or sole aligning means where the ordinary curved 50 shaft of the prior constructions, either of wood or iron, is employed. This aligning feature and structure is applicable to any type of iron club, including the putter.

When addressing the ball and starting the 55 back swing, the flat or substantially flat rear surface of the shaft, provides an aligning feature permitting the golfer to return the club head on the initial part of the upstroke, in alignment with and in the same vertical plane 60 as the ball and intended line of flight thereof. A variance in the path of the club head from this vertical plane, either inside or outside thereof, at the beginning of the back swing, prevents proper execution of the stroke.

In view of the above description and the disclosure in the drawing, it will be readily seen that the invention comprehends a unique construction of shaft or shafts for any type of golf club, from the driver to the putter, in the latter the triangular or substantially triangular shaped shaft providing an efficient aligning means for lining up the ball with the cup or hole. Although the disclosure more particularly refers to a metal shaft construction, it is 75

to be understood that this is but one embodiment of the invention, since wood or other material may be employed in this form of shaft.

Having thus disclosed my invention, I claim:

- 5 1. In a golf club construction, a shaft of approximately triangular cross section with one corner so positioned as to provide a leading front edge of minimum air resistance for the down stroke of the club, the other corners being connected to a portion positioned to provide a substantially flat air resistance area disposed transversely with respect to the direction of movement of the club during the up-stroke thereof.
- 10 2. In a golf club construction, a shaft having a flat rear surface extending the full length thereof, and of a width substantially equal to the maximum width of the shaft, said surface being so positioned as to provide an air resistance area transversely disposed to the direction of movement of the club during the up-stroke thereof.
- 15 3. In a golf club construction, a shaft of approximately triangular cross section, two of the corners thereof being connected by a wall positioned to provide an air resistance area transversely disposed with respect to the direction of movement of the club during the upward stroke thereof, said area being of a width approximately equal to the maximum width of said shaft.
- 20 4. In a golf club construction, a club head and a shaft attached to said head, said shaft having a substantially flat surface of a width approximately equal to the maximum width of the shaft, and disposed in a plane parallel to an edge of the face of the club head, said surface being so positioned as to be the leading edge of the shaft on the back swing of the club.
- 25 5. In a golf club construction, a club head having a triangular opening therein, one wall of said opening lying parallel to an edge of the
- 30 face of the club head and a shaft fitted in said opening and of corresponding cross section, one face of said shaft providing a substantially flat air resistance area transversely disposed with respect to the direction of movement of the club during the up-stroke thereof, said area being of a width substantially equal to the maximum width of said shaft.
- 35 6. In a golf club construction, a shaft provided with a concaved rear surface extending the full length of the shaft and of a width approximately equal to the maximum width of the shaft, said surface being transversely disposed with respect to the direction of movement of the club during the up-stroke thereof and constructed and arranged to provide an air resistance area during said movement.
- 40 7. In a golf club construction, a shaft of approximately triangular cross section with one corner so positioned as to provide a leading edge of minimum air resistance for the down stroke of the club, the sides of the triangle having concaved walls, the rear wall connecting the other corners being transversely disposed with respect to the direction of movement of the club during the up-stroke thereof and constructed and arranged to provide an air resistance area during such movement.
- 45 8. A golf club of the character described comprising a club head having a hosel provided with an opening of triangular cross section, a tapered shaft of similar triangular cross section projected into said opening, one of the surfaces of said shaft being disposed in a plane parallel to an edge of the face of the club head, said surface being of a width approximately equal to the maximum width of the club and so positioned as to provide an air resistance area during said up-stroke.

WILLIAM HUTCHISON. 40
